UNITED STATES PATENT OFFICE.

SYVER LOE, OF MINNEAPOLIS, MINNESOTA.

LACE-FASTENER.

No. 907,257.

Specification of Letters Patent.

Patented Dec. 22, 1908.

Application filed May 20, 1907. Serial No. 374,570.

To all whom it may concern:

Be it known that I, SYVER LOE, a citizen of the United States, residing at Minneapolis, in the county of Hennepin and State of Minnesota, have invented certain new and useful Improvements in Lace-Fasteners; and I do hereby declare the following to be a full, clear, and exact description of the invention, such as will enable others skilled in the art to 10 which it appertains to make and use the same.

My invention has for its object to provide an improved lace fastener for shoes, gloves and other articles having separable flaps or 15 parts that are connected by lacings or strings, and to this end the invention consists of the novel devices and arrangement of parts hereinafter described and defined in the claim.

20 The subject of the present invention is illustrated in the accompanying drawings, wherein like characters indicate like parts throughout the several views.

Referring to the drawings, Figure 1 is a 25 perspective view, showing a pair of my improved lace fasteners applied to the upper edge portions of the shoe flaps. Fig. 2 is a plan view showing one of the improved devices removed from the shoe flap. Fig. 3 is 30 a section taken on the line $x^3 x^3$ of Fig. 2; and Fig. 4 is a section taken on the line $x^4 x^4$ of Fig. 2.

In Fig. 1, the numeral 1 indicates the flaps of a man's shoe, the same having the usual 35 lace hooks 2.

The lacing or shoe string is indicated by the numeral 3.

The entire fastener is stamped from a single piece of thin sheet metal, and the body 4 thereof is preferably given an approximately bell-shaped outline in plan, as best shown in Fig. 2, and it is provided with a U-shaped slit 5 that forms a string clamping tongue 6. The said clamping tongue 6 is left attached 45 to the said body portion 4 at one end, but is pressed laterally so that it diverges slightly

from said body portion, thereby forming a clamping crotch that is adapted to receive the string or lace 3. To prevent cutting of the string the tongue 6 is dished or curved in cross section, and the sides of the U-shaped body portion are dished or curved in an opposite direction, as best shown in Fig. 4. The body portion 4 is provided with three projecting prongs 7 that are adapted to be 55 pressed through the shoe flap and to be clenched on the inner side thereof, thereby securely fastening the device in working position. As shown, one of these prongs 7 is located at the intermediate bowed portion of 60 the body 4, and the other two are located at the extremities of the sides thereof.

The manner in which the lace or string may be secured by the fasteners is illustrated in Fig. 1, it being of course evident that the 65 string may be clamped and securely held when tightly drawn into the diverging crotch formed between the tongue 6 and the sides of the body 4.

The device described may be stamped 70 from a sheet of thin metal and pressed into the form shown in Figs. 2, 3 and 4, ready for application to the shoe flap or other device, at very small cost. In practice the device has been found highly efficient for the purposes had in view. 75

What I claim is:

A lace fastener comprising a thin metal body having side portions and having pressed therefrom but secured thereto at one 80 end a clamping tongue that is dished or curved in cross section and is convex on its inner side, and the side portions of said body being reversely dished in cross section, and the said body having projecting barbs, substantially as described. 85

In testimony whereof I affix my signature in presence of two witnesses.

SYVER LOE.
